Primary Examiner — Mitchell I. Siegel(74) *Attorney, Agent, or Firm* — Laurence A. Greenberg; Werner H. Stemmer; Ralph E. Locher(57) **CLAIM**

The ornamental design for a golf cup ring, as shown and described.

DESCRIPTION

FIG. 1 is a top perspective view of the golf cup ring showing my new design;

FIG. 2 is a bottom perspective view thereof;

FIG. 3 is a front perspective view thereof;

FIG. 4 is a side elevation view thereof;

FIG. 5 is a top plan view thereof; and,

FIG. 6 is a bottom plan view thereof.

The broken lines reading “insignia” on FIGS. 1-3 show the golf cup ring in use as an advertising medium and forms no part of the claimed design. The broken lines extending below the golf cup ring in FIG. 3 show the environmental structure of the golf cup to which it can connect and forms no part of the claimed design.
